UNITED STATES PATENT OFFICE.

FLOYD A. JENKINS, OF OLDEN, TEXAS.

LOAD BINDER.

Application filed February 16, 1927. Serial No. 168,733.

This invention relates to a load binder which is a device for quickly and strongly binding heavy loads for handling with a crane or otherwise. This device which I have provided will permit of almost instantaneous locking of the binder and equally quick taking up of the slack in the rope or chain around the load. Once locked, this binder will not open under stress unless the locking lever is opened by hand.

Referring now to the drawings,

Figure 1 illustrates a perspective view of the device applied to a load such as a stone or a cotton bale and shows the binder in locked position,

Figure 2 shows a perspective view of the device in an open position,

Figure 3 shows a side elevation of the locking member, and

Figure 4 shows a plan view, partly in section of the locking members.

In the drawings, referring particularly to Fig. 2, the reference characters 1—1 represent hooks to be applied to links of a chain or eyelets of a rope, as in Figure 1, 2—2 represent links connecting the hooks to the rotatable ring bolts 3—3, 4 and 5 are shackles, 4 being of ordinary shape while 5 is provided with a notch 6 in one or both of its sides. The top portion 7 of shackle 5 is made convex so that its inner surface conforms to the arcuate portion 8 of lever 11. 9 and 10 are bolts or pins, holding shackles 4 and 5 to the lever 11 at the ends or arcuate portion 8.

Referring now to Figure 3, 3—3 represent the ring bolt shanks, 4 is a shackle of usual shape, 5 is the arcuate shackle, 6 is the notch therein and 7 is the curved surface of the shackle. 8 is the arcuate portion of lever 11 now fitting into shackle 5, the head of bolt of pin 10 engaging notch 6 and being retained there against stress.

Referring to Figure 4, 11 indicates the lever with its arcuate portion 8, lying inside the shackle 5 with the pin 10 of shackle 4 engaged in the notch of shackle 5. In this view, the retaining devices 12, 13, and 14—14, are shown. This device consists of a hole 12 bored in the side of lever 11 approximately at the point shown, containing in said hole

two hard steel balls 14—14 spaced apart and retained by a spring 13. The balls project about the extent of one hemisphere on each side, thereby providing a yieldingly engaging contact in cooperation with correspondingly hemispherical detents 15—15 bored in the inside walls of shackle 5 at substantially the points shown, the operation of the device being as follows:

The device is laid flat upon the load in the position shown in Figure 1, except that the lever 11 lies flat on the load at the left side. The hooks 1—1 are slipped inside the links of the chain or eyelets of the rope passing around the load and the lever is moved to the position shown in Figure 1. In this movement, the pins 9 act as a fulcrum of the lever which pulls shackle 4 over to the notch 6 and engages bolt head 10 therein and finally snaps the balls 14—14 tight in the notches 15—15.

This invention is obviously susceptible of other modifications which I claim as my own if they fall within the scope of the appended claims.

I claim:

1. A load binder comprising a pair of shackles, one of which is provided with one or more retaining notches, a lever, a portion 80 of which is curved, pins passing through the shackle ends and the lever substantially where the curved and straight portions of the lever join, and means whereby to engage one or more of the heads of one of the pins 85 in the retaining notches.

2. A load binder comprising two hooks, swivel means connecting each of said hooks to a shackle, a lever having a curved portion near its end, a pair of shackles, one of 90 which has a curved recess to accommodate the curved portion of the lever, and retaining notches cut therein, pins passing through both shackles and engaging the notches of the shackles when in locked position and 95 spring retaining means carried in said lever to yieldingly lock said lever to said notched shackle when the device is in tightened position.

3. A load binder comprising two hooks, 100 one or more chain links attached thereto, swivels connecting each chain to one of a

pair of shackles, a pair of shackles each connected by means of a pin to a lever having an arcuate portion near its end substantially at the ends of the arcuate portion, one of said shackles insertible bodily into the other shackle, notches cut into the sides of the larger shackle, projecting heads on the pin

holding the smaller shackle to the lever, whereby the smaller shackle may be retained in the larger shackle by means of the notches 10 and spring retaining means for holding the lever into a shackle.

FLOYD A. JENKINS.
